(57) **CLAIM**

The ornamental design for a portable information processing device with detachable keyboard, as shown and described.

DESCRIPTION

FIG. 1 is a perspective view of a portable information processing device with a detachable keyboard in a closed position according to the present invention.

FIG. 2 is a front view of the portable information processing device as shown in FIG. 1.

FIG. 3 is a top view of the portable information processing device as shown in FIG. 1.

FIG. 4 is a bottom view of the portable information processing device as shown in FIG. 1.

FIG. 5 is a left side view of the portable information processing device as shown in FIG. 1.

FIG. 6 is a right side view of the portable information processing device as shown in FIG. 1.

FIG. 7 is a rear view of the portable information processing device as shown in FIG. 1.

FIG. 8 is a perspective view of the portable information processing device as shown in FIG. 1 with the top cover removed and the keyboard detached. The bottom front support leg of the device is extended and the rear support legs of the keyboard are extended.

FIG. 9 is a right side view of the portable information processing device as shown in FIG. 8 with the keyboard support legs recessed; and,

FIG. 10 is top view of the portable information processing device as shown in FIG. 8 with the keyboard functionally connected.

The broken lines throughout the drawing figures are included for the purpose of illustrating a portions of the device that form no part of the claimed design.
